CLAIM

The ornamental design for an automobile air intake duct, as shown and described.

DESCRIPTION

FIG. 1 is a top, left, and front perspective view of an automobile air intake duct showing my new design;

FIG. 2 is a front view thereof;

FIG. 3 is a side view thereof; and,

FIG. 4 is a top view thereof.

The broken lines in the drawings depict portions of the article that form no part of the claimed design.

The drawings and descriptions represent the left side embodiment. The claim is also for a mirror image right side embodiment.

1 Claim, 4 Drawing Sheets
